(57) **CLAIM**

An ornamental design for a waffle cutter, as shown and
described herein.

DESCRIPTION

FIG. 1 is a front perspective view as taken from the upper
right of a waffle cutter of the present invention showing my
new design;

FIG. 2 is a front perspective view thereof as taken from the
bottom right;

FIG. 3 is a front elevational view thereof, the rear elevational
view being a mirror image thereof;

FIG. 4 is a left side elevational view, the right side being a
mirror image thereof;

FIG. 5 is a top plan view thereof; and,

FIG. 6 is a bottom plan view thereof.

1 Claim, 6 Drawing Sheets

FIG. 1

FIG. 2

FIG. 3

FIG. 4
